(57) CLAIM

The ornamental design for a book with strap, as shown and described.

DESCRIPTION

FIG. 1 is a front perspective view of a book with strap embodying my new design;

FIG. 2 is a rear perspective view thereof;

FIG. 3 is a front view thereof;

FIG. 4 is a rear view thereof;

FIG. 5 is a left side elevational view thereof;

FIG. 6 is a right side elevational view thereof;

FIG. 7 is a top view thereof;

FIG. 8 is a bottom view thereof;

FIG. 9 is a front perspective view with the book with strap in the open configuration showing the front cover, showing the thick second page; and,

FIG. 10 is a rear perspective view of the book, showing the thick second page.

The broken lines in the drawings illustrate portions of the book with strap and form no part of the claimed design.
